UNITED STATES PATENT OFFICE.

DANIEL J. MACMILLAN, OF BROOKLYN, NEW YORK.

PNEUMATIC-DISPATCH CARRIER.

Application filed September 6, 1928. Serial No. 304,212.

This invention has reference to devices known as pneumatic dispatch carriers, that are used for conveying small articles, such as documents or money, through a system of 5 tubes, actuated by the air pressure in the tube, such as vacuum by withdrawing the air in advance of the carrier, or by a pressure system, that forces the carrier through the tubes by the air pressure back of the carrier.

10 The object of the present invention is to provide an improved form of carrier that conveys the articles through the system, in which the carrier will be provided at one or both end portions with an improved form of band 15 or ring, of larger diameter than the tubular carrier between the bands, which bands engage the walls of the tube to guide the carrier in its passage, and which bands will reduce the friction tending to retard the advance of the 20 carrier, and which bands will be of greater durability and general efficiency, at the same time of low cost of production.

In the accompanying drawing showing one embodiment of my invention:

25 Figure 1 is a side elevation of the carrier.

Fig. 2 is an axial section through the carrier.

Fig. 3 is a cross section on the line 3-3 of Fig. 2.

30 Fig. 4 is an end view of the carrier.

In devices of this character it has been the custom to provide some form of a band or ring at each end portion of the carrier, that will serve to engage the wall of the tube 35 through which the carrier passes, so that the carrier will be supported and guided at the end portions only, and free from contact with the carrier tube between the bands. Such bands have been formed of suitable material, 40 such as rubber, or even felt has been used for this purpose. With such bands the rubber provides considerable friction tending to retard the movement, and requires considerable pressure of the air to advance the carrier.

45 Where felt rings were employed they are subject to abrasion and rapid wear. On the other hand, if a dead smooth surface is provided on the band, it will not form a good tight fit in the tube, and permit escape of the air under 50 pressure between the band and the tube.

The present invention will overcome these objections and difficulties, by the use of a band that will have a comparatively smooth outer surface for the larger portion of the periphery, while the other portion of the outer surface will have a greater frictional or tight

engagement with the conveying tube, to prevent escape of the air under pressure.

As shown in the drawing the carrier may comprise the usual body in the form of a tube 60 7, of fiber or other suitable material, and which tube is shown as having one end closed by a disc 8, the other end 9 being left open, for the insertion of the documents or other articles to be conveyed by the carrier. 65

At one end of the tube is applied a band or ring 10, formed of a comparatively thick soft textile material, such as felt. This band may be in the form of a strip that is placed around the tube with the ends abutting, and which 70 band or ring is secured tightly to the tube 7 in any suitable manner, such as by a suitable cement or glue.

Around this felt band 10 is applied a band or ring 12, of a comparatively thin strong 75 fabric, such as linen. This band may be of a strip of this material that is wound around the felt band 10, and suitably secured to the belt band, as by a suitable cement or glue; and which band preferably has the ends lapping 80 and is secured by the adhesive. It will be seen that this band 12 is of less width than the inner band 10 of felt, whereby the felt band is exposed at each end portion beyond the edges 85 of the outer band 12, as clearly shown in the drawing; thus providing two narrow bands or zones 13 and 14 at the end portions of the inner left band 10. The outer linen band 12 is preferably tightly applied or secured to the felt band, that will be under slight compression, and this will result in the exposed felt bands at 13 and 14, projecting outwardly a 90 slight distance beyond the intermediate band 12 of linen, as shown in Fig. 2.

At the other end of the carrier tube 7 a felt 95 band 11 is secured to the tube, and which has a linen band 15 secured thereon, the construction of these bands 11 and 15 being substantially identical with the described bands 10 and 12. 100

It will thus be seen that I have provided a carrier with a supporting band at each end portion, that will have the larger portion of the band formed of a strong and durable material and which will not cause undue friction; and which bands will have a smaller zone or portion at the ends that will serve to engage the carrier tube and prevent escape of the air under pressure. It will be further seen that such construction is of low 110 cost, being merely a strip of felt and a strip of linen; and which also can be very easily

and quickly applied, by merely cementing the felt bands in position, and thereupon cementing the linen strip onto the applied felt band.

5 In the use of carriers of this kind, where the carrier rests in a receptacle ready for use, the user cannot tell from merely looking at the carrier which is the open end for the insertion of the article, but must grasp the 10 carrier and turn it up at one end, which may or may not be the open end. With such articles it is customary to grasp the carrier in the left hand with the open end at the right, so that the article can be inserted into the 15 carrier by the right hand; and therefore if the carrier is grasped by the left hand, the closed end may be at the right, and the carrier must be turned end for end before the article can be inserted. To avoid this unnecessary operation, I cause the carrier to be 20 distinctively marked at one end portion, preferably the open end. As shown in the drawing I apply a marking or band 18 to the tube adjacent the band 11, and which 25 may be of a different color from the tube 7. If the latter is of fiber of a red color, this band 18 might be yellow. This will permit the user to grasp the carrier so that the yellow end portion is at the right, and the article 30 can be at once inserted.

What I claim is:—

1. In a pneumatic dispatch carrier, a body tube, a band of comparatively thick textile material such as felt that surrounds the tube 35 at each end and is secured to the tube, and a band of comparatively thin strong textile fabric such as linen that surrounds each said felt band and which is secured thereto, and which outer band is of less width than the 40 inner band whereby the inner band will extend beyond the outer band at each end portion of the inner band to cause the said extended portions of the inner band to project outwardly to engage the conveyor tube.
- 45 2. In a pneumatic dispatch carrier, a body tube, a band of comparatively thick textile material such as felt that surrounds the tube at each end and is secured to the tube by an adhesive, and a band of comparatively thin

strong textile fabric such as linen that surrounds each felt band and which is secured thereto, and which outer band is of less width than the inner band whereby the inner band will extend beyond the outer band at each end portion of the inner band to cause the 55 said extended portions of the inner band to project outwardly to engage the conveyor tube.

3. In a pneumatic dispatch carrier, a body tube, a band of comparatively thick textile 60 material such as felt that surrounds the tube at each end and is secured to the tube, and a band of comparatively thin strong fabric such as linen that surrounds each said felt band and which is secured thereto by a suitable adhesive with the ends lapping, and which outer band is of less width than the 65 inner band whereby the inner band will extend beyond the outer band at each end portion of the inner band to cause the said extended portions of the inner band to project 70 outwardly to engage the conveyor tube.

4. In a pneumatic dispatch carrier, a body tube, a band of comparatively thick textile material such as felt that surrounds the tube 75 at each end and is secured to the tube by an adhesive, and a band of comparatively thin strong fabric such as linen that surrounds each said felt band and which is secured thereto by a suitable adhesive with the 80 ends lapping and which outer band is of less width than the inner band whereby the inner band will extend beyond the outer band at each end portion of the inner band to cause the said extended portions of the inner band to project 85 outwardly to engage the conveyor tube.

5. In a pneumatic dispatch carrier, a body tube, a band of comparatively thick textile material such as felt that surrounds the tube 90 at each end portion and is secured to the tube by adhesive, and a band of comparative thin strong textile fabric such as linen that surrounds each said felt band and is secured thereto by a suitable adhesive.

Signed at New York city, N. Y. on August 31, 1928.
